TOY SPINNING TOP

Peter Balleis, 55 Hermann-Lons-Strasse, Zirndorf,
near Nuremberg, Germany

Filed Apr. 23, 1969, Ser. No. 16,863
Claims priority, application Germany Dec. 23, 1968

Term of patent 7 years

Int. Cl. D21—02

U.S. Cl. D34—15

The figure is a perspective view of the toy spinning top showing my new design.

The characteristic features of my design reside in the particular air and land vehicles in combination with the toy spinning top as shown.

I claim:

The ornamental design for a toy spinning top, as shown and described.
